HEADLIGHT

William L. Bristow, Chicago, Ill., assignor of fifty-one per cent to Walter H. Latimer, Chicago, Ill.

Application March 2, 1938, Serial No. 193,396

1 Claim. (Cl. 240—48.4)

This invention relates to improvements in headlights.

It is an object of the present invention to eliminate the glare produced by the headlights in use at the present time and to effect this elimination of the glare without in any way detracting from the efficiency of the headlight in illuminating the road.

It is, furthermore, an object of the present invention to effectively diffuse a portion of the light issuing from the headlight to destroy the glaring effect in the diffused portion, while another portion of the light issuing from the projector is not interfered with thereby.

Another object of the invention is to provide a headlight structure within which particularly the marginal rays of the beam of light normally issuing from the reflector are diffused, while the central portion or core of the beam remains unaltered, this core of the beam being thrown axially forward at a level at which the glaring effect upon oncoming pedestrians or drivers of cars would not be sensed.

Another object of the invention is to provide a headlight in which the anti-glare or diffusing element can readily be assembled without interfering with the structure of other parts of the ordinary headlight.

The invention also has the object of permitting the headlights of known type and those which are already mounted on automobiles, etc., to be equipped with the anti-glare and light diffusing improvement, and to effect this alteration on the ordinary headlight in such manner that the change can be carried out without requiring special tools or special skill on the part of the operator.

With these and numerous other objects in view, the invention is described in the following specification, in which reference is made to the accompanying drawing:

In the drawing:

Fig. 1 is a vertical sectional view, with parts shown in elevation, of a headlight reflector having the improved attachment;

Fig. 2 shows a front elevation of the headlight with the lens removed;

Fig. 3 shows diagrammatically the shape of the beam of light issuing from the headlight when applied to an automobile, and

Fig. 4 illustrates the illumination outline obtained by the use of the attachment of the present invention.

The majority of the headlights at the present time in use comprise a reflector 1 having a highly polished reflecting surface of paraboloid or ellipsoid shape and having a source of light 2 in the form of an incandescent bulb adjustably mounted on the reflector 1 by means of a socket 3 in such manner that the source of light is disposed as

closely as possible in the focus of the paraboloid or ellipsoid constituting the reflecting surface. In some of the headlights, a parking light 4 also may be mounted on the reflector 1 itself, this parking light usually being of smaller size than the driving light 2, and both of the lamps 2 and 4 being detachably mounted in the sockets 3 and 5 respectively which project through the reflector casing and are held in operative position by suitable bayonet locks 6, 7.

The lamps and reflector are usually protected by means of a casing 8, Fig. 3, and a lens or front glass 9, which is secured on the casing in any desired way, and rests against a strip of cork or the like as indicated at 10.

While theoretically the rays of light emanating from a source located in the focus of a parabolic reflector should be projected strictly parallel to the axis of the parabola, the headlights of modern construction deviate from this strict optical arrangement, for reasons of manufacture or partly intentionally and partly owing to inherent defects, so that a glare is produced which is greatly obnoxious to pedestrians and drivers of vehicles traveling in the opposite direction.

The glare may be primarily due to the fact that the rays of light are directly reflected by the highly polished surface 1 not only parallel to the axis, but also in other directions, and this combination of directly reflected rays of light, while brightly illuminating the road ahead of the car and the space up to relatively great height above the traveling surface also produce the glare which disturbs the driver of oncoming vehicles.

In order to avoid the projection of these rays, which have the glaring qualities, the present invention contemplates the insertion of an attachment which deflects or diffuses certain of the reflected rays or a great portion of the same, directing them back again towards the reflecting surface itself, but now in a general direction different from that which a ray of light originating in the focus of the reflector would have. Owing to this deflection of reflected rays, the rays are again projected from the original reflecting surface but they do not issue from the latter parallel to the axis; they travel at angles to the axis and thereby produce a general diffusion of this light, depriving it of the glaring effect without, however, decreasing the intensity of illumination.

The deflecting surface 11 is located on a ring 12 placed in opposition to the marginal portion of the reflector 1. This surface advisably is a surface of slight conicity with the reduced portion of the reflector ring 12 pointing towards the reflector 1 while the base of the reflector ring 12 preferably lies in or close to the plane in which the outer margin of the reflecting surface 1 also is located. This deflecting conical surface 11 is, therefore, formed as an annular surface leaving 60

a relatively wide inner opening 13 through which the beams of light reflected from the reflector 1 in the ordinary way may be projected.

It will be understood from the above that the rays of light emanating from the marginal portions of the reflector 1 in a direction parallel to the axis of the same will encounter the deflecting surface 11 and since this deflecting surface itself is constructed as a reflector, the light reflected from the surface 1 will once more be reflected from the surface 11 under its angle of incidence. After deflection by the surface 11, it again will be reflected by the marginal or some other portions of the reflector surface so as to be projected at different angles to the axis of the reflector. In this manner the core of light projected from the source of light 2 and from the central portion of the reflecting surface 1, as indicated at 14, is surrounded by a shell 15 of greatly diffused light, and it is this surrounding shell of diffused light which causes the glare from the light issuing from the entire structure to be eliminated.

The aperture of most of the reflectors in use at the present time is a circular aperture, and hence, the outer edge of the deflector ring 12 attached to the reflector 1 also is circular in order to be properly fitted to the reflector. But many of the lamps in use at the present time have a plurality of filaments which either can be supplied with current individually for driving with dimmed light, or which can be supplied with current collectively to intensify the light, when driving with bright light. It is particularly when the lamps 2 are turned on full brightness to project the beam over a relatively greater distance ahead of the car, that the glaring effect produced by this intensified light is sensed and resented by oncoming pedestrians and drivers of vehicles. The filaments 17 in the lamp 2 are frequently arranged in superposition, thereby making the beam of projected light higher than it is wide.

In order to take into consideration this construction of modern incandescent lamps, the opening 13 of the deflector ring 12 may deviate from a circular opening and may be elongated vertically, as shown, when the filaments are arranged in superposition in a vertical plane. The vertical dimension of this inner opening 13 of the deflector ring 12 will then be greater than the horizontal dimension of the same, at the same time thereby creating space through which the light from the parking lamp 4 can be projected through the deflector ring 12.

Owing to the insertion of the deflector ring 12, the area of the core 14 of unaltered light projected directly by the source of light 2 and by the reflector 1 without diffusion may be reduced, but this reduced core is surrounded by a mantle 15 of diffused non-glaring light.

Fig. 4 illustrates the effect of the light upon a board located at a suitable distance from the front of the headlight. The test showed with a lens 9 as furnished for the test a total spread of light in lateral direction of 96 inches. Of this spread of light in lateral directions, the unaffected core had a width of about 28 inches, while the diffused light is effective over an area, which at both sides of the core 14 has a horizontal dimension of 20 inches. A rim of real dim light may then surround this mantle of diffused light, as indicated at 20. The reduction of the intensity of light, and its diffusion,

in proximity to the bright core is of greatest importance in eliminating the concentrated glare of the headlights.

It will be seen from the above that a diffuser or deflector ring 12 for a portion of the light projected by the reflector 1 greatly improves the conditions without in any way interfering with the safety of the driver on whose automobile this attachment has been installed. It will also be seen that the deflector ring 12 which may be a ring of sheet metal having a highly polished reflecting surface 11 on that side which is directed towards the reflector 1, can easily be installed even on headlights which are already in use. In the embodiment illustrated in Figs. 1 and 2, the outer edge of the ring 12 constituting the deflector or diffuser is held in position by the gasket of cork 10 or the like which is frequently interposed between the outer edge of the reflector 1 and the lens 9 of the headlight, this last named lens being secured in any desired way to the headlight casing. It is obvious, furthermore, that for the purpose of improving the appearance of the device, the deflector ring 12 may be provided with a highly polished surface on both of its sides. The high polish on the outer surface of the ring 12 is of benefit in causing illumination of the space directly in front of the casing through the curved portion of the lens 9.

Again, it may be stated that by applying a reflecting coating only to the surface 11 of the deflector ring 12, and making the base or ring itself of a metal differing in color from white, the light diffused by the deflecting surface 11, projected against the reflector, will also show the shade of the color of the base or foundation of the deflector ring 12, also thereby reducing the glare of the white light usually projected by the ordinary headlight. For the sake of appearance, the deflector ring 12 may be provided with a highly polished reflecting surface on both sides, the one that is directed towards the reflector as well as the one which is directed towards the lens or glass of the headlight, although this is not essential for the present invention. In spite of eliminating the glare from the main portion of the light, the core of bright light issuing from the reflector is in every respect sufficient to illuminate the road to the same extent as with the headlights in use at the present time.

I claim:

In a device of the character described, the combination of a reflector having a curved reflecting surface with a focus, a lamp having filaments in vertical arrangement one above the other, said filaments being in the focal plane of the reflecting surface, a ring placed contiguous to the marginal portion of the reflector and having a deflecting surface of slight conicity with the base of the cone in the plane of the outer margin of the reflector, said ring having an inner opening of greater height than width, through which opening the beams of reflected light issuing from the central portion of the reflector will be projected while the light emanating from the marginal portions of the reflector will encounter the deflecting surface of the ring to be reflected thereby into the reflector and to be projected from the reflector at different angles to the axis of the reflector.
